UNITED STATES PATENT OFFICE.

HARRY EHLIG, OF PEARL RIVER, NEW YORK, ASSIGNOR TO GEORGE R. SWART & COMPANY, INC., OF NEW YORK, N. Y., A CORPORATION OF NEW YORK.

FOLDING AND SLITTING MACHINE.

Application filed February 25, 1921. Serial No. 447,836.

To all whom it may concern:

Be it known that I, HARRY EHLIG, a citizen of the United States, and a resident of Pearl River, in the county of Rockland and State of New York, have invented certain new and useful Improvements in Folding and Slitting Machines, of which the following is a specification, reference being made to the accompanying drawings, forming a part thereof.

My invention relates to machines used for folding and slitting printed sheets as they are delivered from a printing-press or other like machine, and the objects of my invention are, among other things, to provide a machine of that type with means by which the rotary cutting bars used for longitudinally slitting the sheets as they are folded may be readily removed from the machine, while the mechanism for delivering such folded and slitted sheets may be easily swung from operative position to afford access to the cutting bars whereby the operator may detach same from the machine without shifting or disturbing any part of their actuating devices. Furthermore my improved machine also enables the different parts with their actuating devices to be readily reassembled in operative position. A further object is to provide simple and highly efficient mechanisms for handling the successive sheets as they are forwarded to my improved folding and slitting machine in which there are a minimum of operative parts so that dependability, accuracy of register, mechanical balance and high speed may be attained. These and other objects will be hereinafter fully set forth and particularly pointed out in the appended claims.

The accompanying drawings illustrate a preferred embodiment of my invention in which—

Fig. 1 is a diagrammatic front elevation showing the arrangement of the cutting bars and the cooperating folding rollers;

Fig. 2 is a sectional view taken on the line 2—2 of Fig. 1, looking in the direction of the arrow, and showing the system of coacting gears for driving the various shafts and bars in my improved machine;

Fig. 3 is an enlarged detailed fragmentary plan view of the slidable support for one end of the cutting bars;

Fig. 4 is an enlarged detailed perspective

view of the supporting block for one end of the cutting bars;

Fig. 5 is a sectional view, enlarged, taken on the line 5—5 of Fig. 1, looking in the direction of the arrow;

Fig. 6 is a sectional view, enlarged, showing the arrangement of folding rollers and coacting folding blade; also the rotary cutting bars and the delivery rollers to carry the folded and slitted sheets onto a delivery board (not shown);

Fig. 7 is an enlarged sectional view showing the latch for holding the delivery rollers and associated devices in place;

Fig. 8 is a detail perspective view of the support for the removable upper delivery roller on the side-frame; and

Fig. 9 is a detail plan view of one of the rotary slitting devices carried by the cutting bars.

Similar numerals refer to similar parts throughout the several figures.

Referring to the drawings, the side frames 10 and 11 support the various parts embodied in my improved machine; from the top of these side frames extend transversely two cooperating folding rollers 12 and 13 mounted on shafts 14 and 15 which are journaled in suitable brackets 16 and 17 located on the top of the side-frames 10 and 11 respectively. Below the folding rollers 12 and 13 are the coacting cutting bars 18 and 19 as shown in Figs. 2 and 6. These folding rollers 12 and 13 and cutting bars 18 and 19 are rotated in unison by the following mechanism best shown in Figs. 1 and 2. Power is derived from any suitable source to rotate the gear wheel 20 which engages with the gear 21 carried by the shaft 15 outside the frame 10 (Fig. 1); the shaft 15 also carries the gear 23 which enmeshes with the gear 22 mounted on the shaft 14. The cutting bars 18 and 19 have coacting driving gears 24 and 25 respectively, the gear 25 being driven by the idler gear 26 secured to the stub-shaft 27 journaled in the bracket 28 in the side-frame 10. The gear 26 is driven from the gear 22 as shown in Fig. 2.

The delivery rollers 29 and 30 which take the slitted folded sheets are mounted on shafts 31 and 32 respectively and are suitably disposed forwardly and below the cutting bars 18 and 19 as shown in Fig. 6; the

left ends of the shafts 31 and 32 (Fig. 1) carry the coacting gears 33 and 34, the gear 34 being driven by the idler gears 35 and 36, gear 36 enmeshing with the idler gear 26, all as shown in Fig. 2.

The two ends of the shaft 31 are journalled in slotted brackets 37 and 38 angularly secured to the side-frames 10 and 11 respectively so that the upper delivery 10 roller 29 with its shaft 31 may be easily lifted out of the slotted brackets 37 and 38, and the teeth of the gears 33 and 34 may also be readily disengaged to permit the removal of the roller 29.

Referring to Figs. 3 and 4, the right ends of the cutting bars 18 and 19 are journalled in the bearings 39 and 40 respectively formed in the supporting block 41 which is slidingly mounted on the L-shaped bracket 20 42 secured to the side-frame 11 by the screws 43. The top surface of the block 41 has the channel 44 formed therein which engages with and slides along the bracket 42 and is held in its full line operative position when the screw bolt 45 passes through the hole 46 of the bracket 42 and engages with the screw-threaded bore 47 cut in the block 41 as shown in Figs. 1, 3 and 5. When the bolt 45 is removed, the block 41 may be 25 readily shifted to the right in Figs. 1 and 3 as indicated by the dotted lines, which causes the right ends of the cutting bars 18 and 19 to slip from their respective bearings 39 and 40. Then such cutting bars 30 35 may be removed from the machine by shifting same to the right in Fig. 1, thereby disengaging the gear 25 from the idler gear 26.

Referring to Figs. 1, 6 and 9, the disk 48 having the annular groove 49 is mounted on the cutting bar 18 while the coacting cutting bar 19 carries the disk 50 having the circular cutting edge 51 to cooperate with the groove 49 to slit the folded sheets fed between them as shown in Figs. 6 and 9. 40 Two or more sets of such slitting devices 45 may be carried by these bars as shown in Fig. 1, and they may be shifted transversely on the bars 18 and 19 to cut the sheets into different sizes as required.

I have provided a removable delivery 50 mechanism with associated elements which may be swung downwardly when it is desired to remove the cutting bars, the upper delivery roller 29 being arranged so as to 55 be raised out of the slotted brackets 37 and 38 as heretofore set forth. In the embodiment shown more particularly in Figs. 1, 2, 5 and 6, the lower delivery roller 30 with its shaft 32 is journalled in the free ends 60 of the rock-arms 52 and 53 rigidly mounted on the cross shaft 54 journalled in the depending brackets 55 and 56 secured to the under sides of the side-frames 10 and 11 respectively. Also carried by the cross- 65 shaft 54 and extending transversely of the

machine between the side frames 10 and 11 is the curved delivery plate 57 secured to arms 58 (only one shown in Fig. 6) rigidly affixed to the shaft 54. The right end of the shaft 54 extends through the bracket 56 70 outside the side-frame 11, and has mounted thereon the latch arm 59 having the handle 60 carrying the latch-pin 61 which is normally pressed forwardly by the coil spring 62 to engage the hole 63 formed in the side-frame 11 as shown in Fig. 7. When the latch-pin 61 is withdrawn from the hole 63 by the handle 60, and the arm 59 is depressed as shown by dotted lines in Fig. 6, the lower delivery roller 30 and also the delivery plate 57 are swung downwardly into the respective dotted line positions shown in Fig. 7, giving free access to the operator to remove the cutting bars 18 and 19 after the upper delivery-roller 29 has been raised 75 out of the slotted brackets 37 and 38. These movable parts can be restored to their full line positions when the latch-arm 59 is again raised so as to bring the latch-pin 61 into engagement with the hole 63 to hold their 80 delivery devices in operative relationship with the slitting devices and upper delivery roller 29.

Referring to Fig. 6, the folding blade 64 is mounted on the end of the rock arm 65 secured to the rock-shaft 66 journalled in the bracket 67 secured to the frame 11. Motion is imparted to the rock-shaft 66 through the arm 68 and reciprocating rod 69 from any convenient source. The blade 64 is lowered to force the sheet 70 between the folding rollers 12 and 13 to be thereafter cut by the slitting devices, the full line showing the flat sheet before the blade 64 has descended while the dotted line illustrates the sheet 70 after the blade 64 has completed its lowering stroke. The sheet 70 is forwarded or advanced over the folding rollers 12 and 13 by any convenient means; in the embodiment shown in Fig. 6 100 the delivery tapes 71 passing around the tape roller 72 perform this preliminary forwarding of the sheet into the full line position shown preparatory to folding and slitting with subsequent delivery from between the delivery rollers 29 and 30 as shown by the dotted line in the lower part of Fig. 6. 105

When it becomes necessary or desirable to remove the cutting bars 18 and 19 from the machine, the operator pulls the handle 60 outwardly to disengage the latch-pin 61 from the hole 63 and then depresses the latch-arm 59 which rotates the shaft 54 in a clock-wise direction as shown in Fig. 6. This movement swings the lower delivery 115 roller 30 and the delivery plate 57 downwardly to the left in Fig. 6 to the dotted line positions there shown, and then the upper delivery roller 29 is lifted out of the slotted brackets 37 and 38, or this delivery 120

roller 29 may be first removed before the operator depresses the latch-arm 59 to lower the delivery roller 30 and plate 57. The bolt 45 is then unscrewed from the hole 46 and bore 47 which enables the operator to pull back the block 41 on the bracket 42 to the right to the dotted line positions shown in Figs. 1 and 3, and the right ends of the cutting bars 18 and 19 thereupon slip from their respective bearings 39 and 40; the operator then moves the cutting bars 18 and 19 to the right in Fig. 1 thereby disengaging their actuating gears 24 and 25 from the gear 26; the cutting bars 18 and 19 may now be lifted forwardly and out of the machine. To reassemble these parts in operative position the reverse of these several steps is followed, the latch-arm 59 and pin 61 bringing the roller 31 and plate 57 back to the full line position shown in Fig. 6.

The invention is not to be limited to the particular constructions shown, nor to any particular constructions by which it may be carried into effect, as many changes and alterations may be made without departing from the principles of the invention, and without sacrificing its chief advantages.

I claim as my invention:—

1. In a machine of the class described, a slitting device comprising mutually parallel rotary cutting bars detachable from the machine, a pair of delivery rollers, a delivery guide plate maintained between the cutting bars and delivery rollers, and means to move said guide plate from between the cutting bars and delivery rollers.
2. In a machine of the class described, a slitting device comprising mutually parallel rotary cutting bars detachable from the machine, a pair of delivery rollers, a delivery guide plate detachably maintained between the cutting bars and delivery rollers, and means to move said guide plate from between the cutting bars and delivery rollers.
3. In a machine of the class described, a slitting device comprising mutually parallel rotary cutting bars detachable from the machine, an upper delivery roller, a lower delivery roller on which the upper roller rests, a delivery guide plate between the cutting bars and delivery rollers, a rocking support for said lower roller and guide plate, means to maintain said support in raised operative position, and means to lower same to inoperative position.
4. In a machine of the class described, a slitting device comprising mutually parallel rotary cutting bars detachable from the machine, an upper delivery roller, a lower delivery roller on which the upper roller rests,

a delivery guide plate between the cutting bars and delivery rollers, a rocking support for said lower roller and guide plate, means comprising a latch to maintain said support in raised operative position, and means to lower same to inoperative position after said latch is released.

5. In a machine of the class described, a slitting device comprising mutually parallel rotary cutting bars detachable from the machine, an upper delivery roller detachably mounted in the machine, a lower delivery roller on which the upper roller rests, a delivery guide plate between the cutting bars and delivery rollers, a rocking support for said lower roller and guide plate, means to maintain said support in raised operative position, and means to lower same to inoperative position.

6. In a machine of the class described, a slitting device comprising mutually parallel rotary cutting bars detachable from the machine, an upper delivery roller detachably mounted in the machine, a lower delivery roller on which the upper roller rests, a delivery guide plate between the cutting bars and delivery rollers, a rocking support for said lower roller and guide plate, means comprising a latch to maintain said support in raised operative position, and means to lower same to inoperative position after said latch is released.

7. In a machine of the class described, a slitting device comprising transversely movable cutting bars and detachable bearings for one end of said bars, a delivery guide plate and a lower delivery roller both mounted on a rocking support below said bars and means to maintain same in raised operative position.

8. In a machine of the class described, a slitting device comprising transversely movable cutting bars and detachable bearings for one end of said bars, a delivery guide plate and a lower delivery roller both mounted on a rocking support below said bars and means comprising a latch to maintain same in raised operative position.

9. In a machine of the class described, a slitting device comprising transversely movable cutting bars and detachable bearings for one end of said bars, a delivery guide plate and a lower delivery roller both mounted on a rocking support below said bars, means comprising a latch to maintain same in raised operative position and means to lower said support to inoperative position after said latch is released.

HARRY EHLIG.
